UNITED STATES PATENT OFFICE.

FRANCIS O. HELTZEL, OF YOUNGSTOWN, OHIO, ASSIGNEE TO TRUSCON STEEL COMPANY,
OF YOUNGSTOWN, OHIO, A CORPORATION OF MICHIGAN.

CONCRETE FORM.

Application filed March 31, 1926. Serial No. 98,777.

The present invention relates to forms used in connection with the construction of concrete roads and the like, and particularly of that character disclosed in 5 my prior Patents Nos. 1,495,305, May 27, 1924, 1,496,933, June 10, 1924, and 1,561,923, Nov. 17, 1925. Such forms consist of side members laid and connected end to end, the side members consisting of upright bodies 10 or webs each with a lower outturned base flange and an upper outturned tread flange. The latter flange has heretofore been disposed at right angles to the web flange. Consequently when a surfacing implement or 15 tool is employed in forming the crown of the road, it runs upon the outer edge of the tread flange. The result is that the road surface is defined by the outer edges of the tread flanges of the opposite forms with a result- 20 ant excessive thickness.

The object of the present invention is to overcome this objection by so forming the tread flange that the inner edges of the form are the starting points for the roadway 25 surface. When it is considered that many miles of roadway are produced, the resultant saving in material is important. And besides, a better upper corner is produced.

In the accompanying drawings:

30 Figure 1 is a sectional perspective view of portions of a roadway formed with the completed road bed therein.

Figure 2 is a detail sectional view on an enlarged scale showing the improved structure in full lines and the original structure in dotted lines in order to indicate the resultant benefits of the former.

The form members are generally designated by the reference numeral 3, and each 40 consists of a vertical wall or web 4, with an outstanding base flange 5 and an outstanding tread or guide flange 6 that may be reinforced by a downturned rib 7. It will be understood that these may be made in sections, and connected by any suitable means, as for example, those disclosed in my above mentioned patents. The tread or guide flange 6 of each member, instead of being at 45 right angles, has an outward and downward inclination, preferably at substantially the angle of the surface of the crown of the roadway to be constructed, as illustrated in full

lines in Figure 2. In other words, the upper surface 8 of the guide or tread flange 6 is substantially a continuation of the upper 55 surface 9 of the concrete or other roadway.

It will thus be evident that when a surfacing tool or implement is moved along opposite guide flanges 6 the surface 9 of the roadway will be at the level of the inner edges 60 of the flanges 6, or in other words, constitute continuations of the upper surfaces thereof, whereas with the former construction, as indicated in dotted lines in Figure 2, when the upper face 8^a is at right angles to 65 the body 4, the concrete surface 9^a starts at the outer edge of the flange, and an increase in the thickness of the road bed is thus produced, which makes a decided increase in the amount of material used, particularly on 70 long stretches. Besides it leaves outstanding flanges overhanging and extending beyond the body of the road bed.

From the foregoing, it is thought that the construction, operation and many advantages of the herein described invention will be apparent to those skilled in the art, without further description, and it will be understood that various changes in the size, shape, proportion and minor details of construction 80 may be resorted to without departing from the spirit or sacrificing any of the advantages of the invention.

What I claim is:

1. A form for crowned concrete roadways 85 and the like comprising spaced concrete confining side walls, having oppositely outstanding guide or track flanges along their upper edges, the said flanges of the two side walls having their upper faces inclining outwardly and downwardly to correspond substantially to the crowned surface of the roadway.

2. A form rail having an upper beveled flange.

3. A form rail having a tread flange sloping from the rail web.

4. A form rail having a web and an upper flange, with said flange so formed as to provide a single line of wheel contact directly 100 above the web.

In testimony whereof, I affix my signature.

FRANCIS O. HELTZEL.
